UNITED STATES PATENT OFFICE

2,442,031

REFRIGERATOR CAR DOOR

Wilfred A. Beauchamp, Chicago, Ill., assignor to
The Youngstown Steel Door Company, Cleve-
land, Ohio, a corporation of Ohio

Application April 27, 1946, Serial No. 665,463

23 Claims. (Cl. 20—23)

1

This invention relates to refrigerator car doors and more particularly to doors adapted to be moved laterally into door openings in said cars in flush relationship with the walls thereof and out of said door openings for sliding movement along said walls.

It is an object of this invention to provide doors for refrigerator cars movable into and out of door openings in said cars wherein means is provided which shall greatly enhance the ease of movement of said doors into the door openings.

A further object is to provide means for doors for refrigerator cars so accessible both from the ground and from platforms that a more effective utilization of the force applied to move said doors into their openings is obtained.

A further object is to provide mechanism for doors for refrigerator cars embodying vertically disposed, rotatable bars and associated means so related to the bars that a more effective utilization of force is obtained to impart rotation to the bars and move said doors into their openings.

Other objects of the invention will become clear as the description thereof proceeds.

In the drawings forming part of this specification:

Fig. 1 is a fragmentary elevation of a side wall of a refrigerator car to which is applied a sliding door embodying the instant invention, the door being shown in closed position.

Fig. 2 is a horizontal section taken on line 2—2 of Fig. 1 showing in dot and dash lines the position of the levers when initial contact has been made between the door and the packing.

Fig. 3 is a horizontal section similar to Fig. 2 showing the door moved out of the door opening and in position for sliding movement in opening direction.

Fig. 4 is a vertical section taken on line 4—4 of Fig. 1.

Fig. 5 is a vertical section taken on line 5—5 of Fig. 1 corresponding to the showing of Fig. 2.

Fig. 6 is an enlarged elevational detail of a portion of the vertical lever and the bracket slidably and swingably carrying the lever.

Fig. 7 is an enlarged elevational detail of a device for locking and sealing the vertical lever.

Fig. 8 is a vertical section taken on line 8—8 of Fig. 7.

Referring to the drawings wherein a preferred embodiment of the invention is illustrated, reference numeral 10 designates a side wall of a refrigerator car within which a door opening 11 is provided and adapted to be closed by means of a longitudinally sliding and laterally swinging

2

door 12. The refrigerator car is of a type whose construction is well known in the art so that detailed description is not necessary. As is customary in this type of freight car, sealing means 13, known to the art as LaFlare packing, extends continuously across the top and along the sides of the door opening as is more clearly illustrated in Figs. 2 and 4 of the drawings. This packing is adapted to be engaged against the compression 10 of the customary springs 14 employed with the packing by the top and sides of the door 12 which customarily completely fills the door opening so that the outer and inner faces thereof lie flush with the outer sheathing and inner lining of the car. In this manner the indicated edges of the door are sealed. Sealing means is also provided for the lower edge of the door and may be of any desired construction. The sealing means illustrated in Fig. 4 of the drawings embodies two 20 sealing strips 15 and 16 secured respectively to the car and to the inner face of the door and related as shown when the door is closed.

The door 12 may be of any desired construction. As illustrated, it embodies a rectangular metallic frame formed of upper and lower angular rails 17 and 18 and vertical stiles 19 and 20. The metallic frame is covered by a metallic panel 21. Wooden filler members 22 and 23 are seated in the rails 17 and 18 and similar wooden filler 30 members, one of which is shown at 24 are seated in the vertical stiles 19 and 20. These filler members extend inwardly and to their inner ends a veneer panel 25 is secured. A space is thus provided between the outer metallic panel 21 and the inner veneer panel 25 within which any desired insulation (not shown) may be secured in order to properly insulate the door.

Mechanism is provided with doors of the type described above for moving the door 12 laterally of the car into and out of the door opening 11. As more clearly shown in Figs. 1 and 4 of the drawings, this mechanism embodies upper and lower track members 26 and 27 secured to the car above and below the door opening 11. Vertically disposed bars 28 and 29 are rotatably mounted upon the outer face of the door by means of a plurality of castings 30, 31, and 32 and 33, 34, and 35. Crank members 36 and 37 are secured to the upper ends of the bars 28 and 29 and are rotatably secured as by means of bolts 38 and 39 to roller hangers 40 and 41. These hangers carry rollers 42 and 43 which are adapted to roll along the upper track 26 and are formed with hook-shaped portions such as 44 50 which embrace a portion of the upper track 26

as shown in Fig. 4 of the drawings to prevent accidental disengagement of the upper portion of the door from the track.

Crank members 45 and 46 are secured to the lower portion of the rotatable bars 28 and 29 and are rotatably secured to hangers 40^a and 41^a formed with hook members such as 47 adapted to embrace a portion of the lower track 27 so as to prevent accidental disengagement of the lower portion of the door from the car side. The hook portions 44 and 47 serve also to guide the door in its sliding movement longitudinally of the car.

Collars 48 and 49 are rigidly secured to the rotatable bars 28 and 29 and to these collars are pivotally secured the bar operating levers 50 and 51.

The operation of the bars 28 and 29 by means of the levers 50 and 51 in order to force the door into the door opening against the spring pressed LaFlare packing and to move the door out of the door opening so that it may be slid longitudinally of the car to open position will be readily understood by those skilled in the art. The operation of forcing the door into the door opening, however, by means of levers such as 50 and 51 has in the past been exceedingly difficult, particularly where, as is very frequently the case, the closing operation must be performed from the ground. In this situation the operator must raise his hands above his head in order to grasp the levers 50 and 51 to exert a force upon the door to move it into the door opening and the force which he can exert for this purpose is relatively small and ineffectively utilized. The instant invention provides a mechanism whereby the lateral movement of the door into its opening can be accomplished with far greater facility and with the effective utilization of the force applied for this purpose. Moreover, the invention accomplishes this end with equal ease from the ground and from a platform.

This mechanism embodies a bracket 52 secured as by means of riveting to the outer metallic panel 21 of the door above the levers 50 and 51. The sides 53 and 54 of the bracket are formed with inclined slots one of which is shown at 55. The inner wall 56 of the bracket is open and the slots extend outwardly from the inner wall. This permits the assembly of the vertically disposed lever 57 with the bracket 52 by the insertion of pins 58 and 59 provided on the bracket into the slots such as 55. After assembly has been completed the bracket 52 is riveted to the door panel 21 so that the lever 57 is then securely retained upon the door.

The vertical lever 57 extends downwardly beyond the horizontal levers 50 and 51 as more clearly shown in Fig. 1 and at its lower end is formed with a projection 60 which prevents the foot of the operator from slipping off the lever when it is actuated to force the door into the door opening while the operator is standing on a platform. Intermediate its ends the vertical lever 57 is formed with oppositely extending ears 61 and 62 which when the lever is actuated for its intended purpose are in alignment with the horizontal levers 50 and 51. The horizontal levers are so designed that when the door is in closed position they terminate short of the vertical lever 57 but are overlapped by the ears 61 and 62 on the latter lever.

The vertical lever 57 provides means easily accessible and operable both from the ground and from platforms for effectively applying a

force to the adjacent ends of the levers 50 and 51 in order to force the door 10 into the door opening 11. Assuming the door to be moved so as to lie in front of the door opening, as more clearly shown in Fig. 3 of the drawings, and it is desired to force the door into the door opening, the horizontal levers 50 and 51, which at this time hang vertically from the arms 48 and 49 and are received within the jaws 63 and 64 formed on the brackets 31 and 34, are swung out of these jaws and into a horizontal position. The horizontal levers are then swung toward each other thereby imparting rotation to the bars 28 and 29 and to the cranks fastened to the upper and lower ends of the bars. The rotation of the bars and their cranks moves the door partly into the door opening with relatively little effort. When the door contacts the LaFlare packing, however, a far greater effort is required to move the door completely into the door opening. When this contact occurs, the horizontal levers 50 and 51 which lie outwardly of the ears 61 and 62 are supported upon inclined ledges 65 and 66. The operator then slides the vertical lever 57 upwardly, this being permitted by the sliding of the pins 58 and 59 in the slots such as 55 formed in the bracket 52. The upward movement of the vertical lever 57 raises the ears 61 and 62 until they lie above the horizontal levers 50 and 51 thereby permitting the vertical lever to be swung outwardly between the adjacent ends of the horizontal levers. The vertical lever 57 is then lowered so that the ears 61 and 62 overlap the adjacent ends of the horizontal levers 50 and 51. A force is then applied to the lower end of the vertical lever 57 so as to swing it inwardly and during this swinging movement the ears 61 and 62 being engaged with the horizontal levers 50 and 51 apply a substantial force thereto so as to readily complete the lateral movement of the door into the door opening.

After the door has been fully closed as set forth above, the vertical lever 57 is locked and sealed. For this purpose the vertical lever is provided with a stud 67 which engages and automatically raises a catch 68 pivotally supported by means of a bracket 69 set into the door and secured as by means of rivets to the outer metallic panel 21 as more clearly shown in Figs. 5 and 8 of the drawings. To insure that the pivot catch 68 will be in proper position for engagement by the stud 67, the catch is provided with a tail piece 70 which engages the bracket 69 for the purpose indicated. The tail piece 70 serves the further purpose of insuring locking engagement between the catch 68 and the stud 67, this being accomplished by its cooperation with a projection 71 extending inwardly from the inner edge of the vertical lever. Should the catch 68 fail to have locking engagement with the stud 67 when the vertical lever 57 is swung inwardly, the projection 71 will engage the tail piece 70 and swing the catch downwardly into locking engagement with the stud.

When the vertical lever 57 is in locked position as shown in full lines in Fig. 5 of the drawings, it is sealed by means of a seal (not shown) which passes through a seal slot 72 formed in a flange 73 on the bracket 69, across the outer edge of the lever and through a seal slot 74 formed in the catch 68. When the vertical lever 57 is in this position the projection 71 lies below a hub 75 formed on the pivoted catch 68 and cooperates therewith to prevent upward vertical movement

of the lever. This insures against disengagement of the stud 67 from the pivoted catch without breaking the seal.

The instant invention has been described particularly in its relationship to laterally movable doors for refrigerator cars to which it is especially applicable. It is to be understood, however, that the invention is not limited to such doors for refrigerator cars only but is applicable as well to laterally movable doors for other types of railway cars and to other types of doors for refrigerator and other railway cars where the doors are disposed in the door openings.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a sliding door for railway cars having a wall provided with a door opening, means embodying vertically disposed bars rotatably mounted on said door for supporting said door for longitudinal movement along said car and transverse movement into and out of said door opening, levers mounted on said bars, said levers being swingable horizontally to impart rotation to said bars, and a vertically swingable lever mounted on said door, said latter lever being engageable with said horizontally swingable levers to impart swinging movement thereto.

2. In a sliding door for railway cars having a wall provided with a door opening, means embodying vertically disposed bars rotatably mounted on said door for supporting said door for longitudinal movement along said car and transverse movement into and out of said door opening, horizontally swingable levers mounted upon said bars for imparting rotation thereto, said levers being spaced apart, a vertically swingable lever mounted on said door and extending below said first mentioned levers, said vertically swingable lever being swingable downwardly between said first mentioned levers, and ears on said vertically swingable lever engageable with said first mentioned levers for imparting horizontal swinging movement thereto.

3. In a sliding door for railway cars having a wall provided with a door opening, means embodying vertically disposed bars, rotatably mounted on said door for supporting said door for longitudinal movement along said car and transverse movement into and out of said door opening, levers mounted on said bars, said levers being swingable horizontally to impart rotation to said bars, a vertically swingable lever mounted on said door, said latter lever being engageable with said horizontally swingable levers to impart horizontal swinging movement thereto, and means on said door for supporting said first mentioned levers in position for engagement by said vertically swingable lever.

4. In a sliding door for railway cars having a wall provided with a door opening, means embodying vertically disposed bars rotatably mounted on said door for supporting said door for longitudinal movement along said car and transverse movement into and out of said door opening, horizontally swingable levers mounted upon said bars for imparting rotation thereto, said levers being spaced apart, a vertically swingable lever mounted on said door and extending below said first mentioned levers, said vertically

swingable lever being swingable downwardly between said first mentioned levers, ears on said vertically swingable lever engageable with said first mentioned levers for imparting horizontal swinging movement thereto, and means on said door for supporting said first mentioned levers in position for engagement by said ears.

5. In a sliding door for railway cars having a wall provided with a door opening, means embodying vertically disposed bars rotatably mounted on said door for supporting said door for longitudinal movement along said car and transverse movement into and out of said door opening, levers mounted on said bars, said levers being swingable horizontally to impart rotation to said bars, a vertically swingable lever mounted on said door, said latter lever extending below said first mentioned levers and being engageable therewith to impart horizontal swinging movement thereto, means on said vertically swingable lever, and means on said door automatically engageable with said lever means to lock said lever after said door has been moved into said door opening.

6. In a sliding door for railway cars having a wall provided with a door opening, means embodying vertically disposed bars rotatably mounted on said door for supporting said door for longitudinal movement along said car and transverse movement into and out of said door opening, levers mounted on said bars, said levers being swingable horizontally to impart rotation to said bars, a vertically swingable lever mounted on said door, said latter lever extending below said first mentioned levers and being engageable therewith to impart horizontal swinging movement thereto, a stud on said vertically swingable lever, a locking member pivotally mounted on said door, means on said locking member engageable with said door to position said locking member for automatic locking engagement with said stud after said door has been moved into said door opening, and means on said vertically swingable lever engageable with said means on said locking member to insure locking engagement between said locking member and said stud.

7. In a sliding door for railway cars having a wall provided with a door opening, means embodying vertically disposed bars rotatably mounted on said door for supporting said door for longitudinal movement along said car and transverse movement into and out of said door opening, horizontally swingable levers mounted upon said bars for imparting rotation thereto, said levers being spaced apart, a vertically slidable and swingable lever mounted on said door and extending below said first mentioned levers, said slidable and swingable lever being swingable downwardly between said first mentioned levers, and ears on said slidable and swingable lever engageable with said first mentioned levers for imparting swinging movement thereto.

8. In a sliding door for railway cars having a wall provided with a door opening, means embodying vertically disposed bars rotatably mounted on said door for supporting said door for longitudinal movement along said car and transverse movement into and out of said door opening, horizontally swingable levers mounted upon said bars for imparting rotation thereto, said levers being spaced apart, a vertically slidable and swingable lever mounted on said door and extending below said first mentioned levers, said slidable and swingable lever being swingable downwardly between said first mentioned levers,

ears on said slideable and swingable lever engageable with said first mentioned levers for imparting swinging movement thereto, and means on said door for supporting said first mentioned levers in position for engagement by said ears.

9. In a sliding door for railway cars having a wall provided with a door opening, means embodying vertically disposed bars rotatably mounted on said door for supporting said door for longitudinal movement along said car and transverse movement into and out of said door opening, horizontally swingable levers mounted upon said bars for imparting rotation thereto, said levers being spaced apart, a vertically slid-able and swingable lever mounted on said door and extending below said first mentioned levers, said slid-able and swingable lever being swingable downwardly between said first mentioned levers, ears on said slid-able and swingable lever engage-able with said first mentioned levers for imparting swinging movement thereto, and means on said lever and said door for automatically locking said lever after said door has been moved into said door opening.

10. In a sliding door for railway cars having a wall provided with a door opening, means embodying a vertically disposed bar rotatably mounted on said door for supporting said door for longitudinal movement along said car and transverse movement into and out of said door opening, a lever mounted on said bar, said lever being swingable horizontally to impart rotation to said bar and a vertically swingable lever mounted on said door, said latter lever being engageable with said horizontally swingable lever to impart horizontal swinging movement thereto.

11. In a sliding door for railway cars having a wall provided with a door opening, means embodying a vertically disposed bar rotatably mounted on said door for supporting said door for longitudinal movement along said car and transverse movement into and out of said door opening, a horizontally swingable lever mounted on said bar for imparting rotation thereto, a vertically slideable and swingable lever mounted on said door and extending below said first mentioned lever in spaced relation thereto, and an ear on said slideable and swingable lever, said latter lever being swingable downwardly and said ear being engageable with said first mentioned lever for imparting horizontal swinging movement thereto.

12. In a sliding door for railway cars having a wall provided with a door opening, means embodying a vertically disposed bar rotatably mounted on said door for supporting said door for longitudinal movement along said car and transverse movement into and out of said door opening, a horizontally swingable lever mounted on said bar for imparting rotation thereto, a vertically slideable and swingable lever mounted on said door and extending below said first mentioned lever in spaced relation thereto, an ear on said slideable and swingable lever, said latter lever being swingable downwardly and said ear being engageable with said first mentioned lever for imparting horizontal swinging movement thereto, and means on said door for supporting said first mentioned lever in position for engagement by said ear.

13. In a railway car having a wall member provided with a door opening and a door member, means embodying a vertically disposed bar rotatably mounted on said door member for imparting movement thereto into and out of said

door opening, a lever mounted on said bar, said lever being swingable horizontally to impart rotation to said bar, and a vertically swingable lever mounted on one of said members, said latter lever being engageable with said horizontally swingable lever to impart horizontal swinging movement thereto.

14. In a railway car having a wall member provided with a door opening and a door member, means embodying a vertically disposed bar rotatably mounted on said door member for imparting movement thereto into and out of said door opening, a horizontally swingable lever mounted on said bar for imparting rotation thereto, a vertically slideable and swingable lever mounted on one of said members and extending below said first mentioned lever in spaced relation thereto, and an ear on said slideable and swingable lever, said latter lever being swingable downwardly and said ear being engageable with said first mentioned lever for imparting horizontal swinging movement thereto.

25 15. In a railway car having a wall member provided with a door opening and a door member, means embodying a vertically disposed bar rotatably mounted on said door member for imparting movement thereto into and out of said door opening, a horizontally swingable lever mounted on said bar for imparting rotation thereto, a vertically slidable and swingable lever mounted on one of said members and extending below said first mentioned lever in spaced relation thereto, an ear on said slidable and swingable lever, said latter lever being swingable downwardly and said ear being engageable with said first mentioned lever for imparting horizontal swinging movement thereto, and means on said door member for supporting said first mentioned lever in position for engagement by said ear.

16. In a sliding door for railway cars having
a wall provided with a door opening, means
embodying vertically disposed bars rotatably
mounted on said door for supporting said door
for longitudinal movement along said car and
transverse movement into and out of said door
45 opening, horizontally swingable levers mounted
upon said bars for imparting rotation thereto,
said levers being spaced apart, a vertically slid-
able and swingable lever mounted on said door
50 and extending below said first mentioned levers,
said slidable and swingable lever being swing-
able downwardly between said first mentioned
levers, ears on said slidable and swingable lever
engageable with said first mentioned levers for
55 imparting swinging movement thereto, and means
for preventing sliding movement of said vertically
slidable and swingable lever.

17. In a sliding door for railway cars having a wall provided with a door opening, means embodying vertically disposed bars rotatably mounted on said door for supporting said door for longitudinal movement along said car and transverse movement into and out of said door opening, horizontally swingable levers mounted upon said bars for imparting rotation thereto, said levers being spaced apart, a vertically slidable and swingable lever mounted on said door and extending below said first mentioned levers, said slidable and swingable lever being swingable downwardly between said first mentioned levers, ears on said slidable and swingable lever engageable with said first mentioned levers for imparting swinging movement thereto, means for locking said vertically slidable and swingable lever against swinging movement and means for pre-

venting sliding movement of said vertically slideable and swingable lever.

18. In a railway car having a wall member provided with a door opening and a door member, means embodying a vertically disposed bar rotatably mounted on said door member for imparting movement thereto into and out of said door opening, a horizontally swingable lever mounted on said bar for imparting rotation thereto, a vertically slideable and swingable lever mounted on one of said members and extending below said first mentioned lever in spaced relation thereto, an ear on said slideable and swingable lever, said latter lever being swingable downwardly and said ear being engageable with said first mentioned lever for imparting horizontal swinging movement thereto, and means for preventing sliding movement of said vertically slideable and swingable lever.

19. In a railway car having a wall member provided with a door opening and a door member, means embodying a vertically disposed bar rotatably mounted on said door member for imparting movement thereto into and out of said door opening, a horizontally swingable lever mounted on said bar for imparting rotation thereto, a vertically slideable and swingable lever mounted on one of said members and extending below said first mentioned lever in spaced relation thereto, an ear on said slideable and swingable lever, said latter lever being swingable downwardly and said ear being engageable with said first mentioned lever for imparting horizontal swinging movement thereto, means for locking said vertically slideable and swingable lever against swinging movement and means for preventing sliding movement of said vertically slideable and swingable lever.

20. In a railway car having a wall member provided with a door opening and a door member, means embodying a vertically disposed bar rotatably mounted on said door member for imparting movement thereto into and out of said door opening, a horizontally swingable lever mounted on said bar for imparting rotation thereto, a vertically slideable and swingable lever mounted on one of said members and extending below said first mentioned lever in spaced relation thereto.

an ear on said slideable and swingable lever, said latter lever being swingable downwardly and said ear being engageable with said first mentioned lever for imparting horizontal swinging movement thereto, means on said door member for supporting said first mentioned lever in position for engagement by said ear, and means for preventing sliding movement of said vertically slideable and swingable lever.

10 21. In a sliding door for railway cars having a wall provided with a door opening, means embodying vertically disposed bars rotatably mounted on said door for supporting said door for longitudinal movement into and out of said car and traverse movement into and out of said door opening, levers mounted on said bars, said levers being swingable horizontally to impart rotation to said bars, and a vertically movable member mounted on said door, said member being engageable with said horizontally swingable levers to impart swinging movement thereto.

25 22. In a sliding door for railway cars having a wall provided with a door opening, means embodying a vertically disposed bar rotatably mounted on said door for supporting said door for longitudinal movement along said car and traverse movement into and out of said door opening, a lever mounted on said bar, said lever being swingable horizontally to impart rotation to said bar, and a vertically movable member mounted on said door, said member being engageable with said horizontally swingable lever to impart horizontal swinging movement thereto.

30 23. In a railway car having a wall member provided with a door opening and a door member, means embodying a vertically disposed bar rotatably mounted on said door member for imparting movement thereto into and out of said door opening, a lever mounted on said bar, said lever being swingable horizontally to impart rotation to said bar, and vertically movable means mounted on one of said members, said latter means being engageable with said horizontally swingable lever to impart horizontal swinging movement thereto.

35 40 45 WILFRED A. BEAUCHAMP.
